UNITED STATES PATENT OFFICE.

FRANK R. McBERTY, OF EVANSTON, AND EDWARD B. CRAFT, OF CHICAGO, ILLINOIS, ASSIGNORS TO WESTERN ELECTRIC COMPANY, OF CHICAGO, ILLINOIS, A CORPORATION OF ILLINOIS.

SPRING-JACK FOR TELEPHONE-SWITCHBOARDS.

No. 853,370.

Specification of Letters Patent.

Patented May 14, 1907.

Application filed December 10, 1904. Serial No. 236,278.

To all whom it may concern:

Be it known that we, FRANK R. McBERTY and EDWARD B. CRAFT, citizens of the United States, residing at Evanston and Chicago, respectively, in the county of Cook and State of Illinois, have invented a certain new and useful Improvement in Spring-Jacks for Telephone-Switchboards, of which the following is a full, clear, concise, and exact description:

Our invention relates to a strip of spring-jacks for telephone switchboards, and its object is to provide an improved construction which will be compact, light, strong, simple and cheap to manufacture, and which will insure reliable switching action and proper insulation of the conducting parts.

In accordance with our invention, the tongue or connecting strip which extends rearwardly from the test thimble or tube at the front of the jack, is bent at a point between the front and rear supporting strips, so that the rear portion of said tongue is disposed on edge or in a vertical plane, and is adapted to form a rigid backing piece for the line contact springs of the jack, which are also disposed on edge parallel to said tongue and preferably on either side thereof. A pair of insulated contact springs may be mounted on edge between the rear portion of the tongue and one of the line springs, to be operated when said line spring is flexed by the insertion of the plug in the jack. The contact surfaces of the jack are thus disposed on edge to avoid accumulations of dust thereon, while providing for an extremely compact arrangement of the parts, with great strength and rigidity, and efficient insulation.

The vertically-disposed portion of the tongue or connecting strip before referred to is united with the test tube or thimble by means of an arm or arms which may be bent to lie flat above or below the ends of the line springs and out of the path of the plug. Preferably the test tube and its connecting strip are formed integrally from a sheet-metal blank or punching, one end of said blank being rolled to form the tube, and the rear portion of the connecting strip being united with the tube by two curved arms branching from the edges thereof, said arms being bent into parallel planes at right an-

gles to the plane of the rear portion. The connecting strip thus forms a rigid connection or support between the front and rear insulating supporting strips, which is particularly adapted to withstand the stresses in all directions to which the springjack will be subjected. Said connecting strip further forms a substantial backing piece for the contact springs, whereby they may be maintained in their proper positions relative to each other and to the test tube. Such construction is furthermore especially adapted for "cut-off jacks", where a switch contact is required in addition to the ordinary line springs.

In the accompanying drawing, Figure 1 is a plan view of a strip of springjacks embodying our invention; Fig. 2 is a front elevation showing the openings adapted to receive the plugs; Fig. 3 shows an end view of the strip and a connecting plug in position to be inserted therein; Fig. 4 is an isometric view showing the several parts of a springjack ready for assembly; Fig. 5 is a detail view of the blank or punching from which the test tube and its connecting strip are formed.

The same parts are indicated by similar letters of reference throughout the several figures of the drawing.

As shown, the strip of springjacks comprises front and rear supporting strips *m h* of insulating material, and springjack parts mounted therein. Each of the springjacks illustrated comprises the usual line springs *a b*, a test tube or thimble *c* and cut-off contacts *e e'*. The test thimble *c* is provided with a connecting strip or tongue extending to the rear supporting strip, said tongue comprising a flat rear portion *d'* disposed in a vertical plane in a groove in the rear supporting strip, and curved arms uniting said rear portion with the tube, said arms branching from the upper and lower edges of the rear portion and being turned over to lie in parallel planes at right angles to the plane of the rear portion, joining the rear edge of the test tube at the top and bottom thereof, respectively. The test tube with its connecting strip including the arms *d d* may be conveniently made from a flat metal punching of the form shown in Fig. 5, one end of the punching being rolled up to form the tube, and the curved arms *d d* being

bent at the edge of the straight portion d' into parallel planes at right angles to the plane of said straight portion.

The rear portion of the strip d' forms a rigid backing piece or frame for the contact springs and their insulating strips going to build up the springjack. These parts are assembled in parallel planes in a transverse slot or groove in the rear supporting strip, the line 5 springs projecting forward with their free ends immediately behind the hole in the test thimble, in position to engage the contacts of an inserted plug. The line springs are disposed as shown on opposite sides of the backing strip d' , the movement of 10 the springs being limited thereby. Insulating strips d^2 d^2 are provided on either side of the backing strip, said strips extending to the front end of the straight portion d' , as shown.

15 The line spring a , which in this instance is the long line spring, is arranged to operate a pair of contact springs e e' , which, together with their insulating strips, lie between said line spring and the insulating strip d^2 which 20 is at the same side of the backing piece d' . The spring a carries an insulating spacer f which is adjusted to normally press the contact spring e against its mate e' , but when spring a is flexed, as by the insertion of a connecting plug, such as the plug g shown in Fig. 25 3, the contact spring e is left free to move by its own tension out of engagement with its contact anvil e' . These auxiliary contacts e e' may be used in accordance with the well 30 known practice, to control the circuit of a subscriber's line signal.

The rear ends of the springs and tongue d' of the jacks of the strip, together with the several insulating strips interposed between 40 such parts, are wedged edgewise into a transverse groove h' in the rear insulating strip or block h , which serves as a rigid support for said springs. It will be noted that the backing pieces or tongues d' of the several jacks 45 serve as a support for the insulating block h , each tongue also forming the frame or base upon which the parts of its own jack are as-

sembled. The springs and contacts of a jack being mounted on edge and parallel to one another, make a compact construction, and allow dust and other foreign matter to fall between them instead of collecting on their surfaces and interfering with the proper operation of the device. Metal binding strips i i' may be secured to the top and bottom of the strip h by screws, an insulating strip k being interposed between the plate i and the supporting strip h over the grooves therein as shown, whereby the parts of the jack are held against removal from said grooves.

We claim:—

1. In a springjack, the combination with a pair of line springs and a test piece, said test piece comprising a tube, rearwardly extending tongue and arms uniting them, said parts being stamped from a single piece of metal, the line springs being located on opposite sides of said tongue and insulated therefrom, of a pair of contact springs lying next to each other between the tongue and one of said line springs, said springs being insulated from said tongue and line spring and arranged to be operated when the line spring is flexed, and an insulating block at the rear of the jack, in which said springs and tongue are mounted.

2. A sheet metal blank for a springjack test thimble and connecting strip, consisting of a front portion adapted to be rolled to form the tube, a rear portion adapted to serve as a connector, and two arms joining said front and rear portions, said arms branching from said front portion at a diverging angle and curving to join said rear portion.

In witness whereof, we hereunto subscribe our names this 24th day of October A. D., 1904.

FRANK R. McBERTY.
EDWARD B. CRAFT.
